CLAIM

The new, original, and ornamental design for a dual pack wrapper, as shown and described.

DESCRIPTION

FIG. 1 is a front elevational view of a dual pack wrapper showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The phantom-line and/or broken-line depictions in the drawings are shown for environmental and illustrative purposes only, and form no part of the claimed design of the present invention.

The nature and intended use of the article of manufacture in which the design of the present invention is embodied is a dual pack wrapper, for example, a wrapper including two packs to carry food, or similar items.
